UNITED STATES PATENT OFFICE.

HENRY N. NEIREITER, OF DECATUR, INDIANA.

TILE-DRAIN INLET FOR SURFACE WATER.

SPECIFICATION forming part of Letters Patent No. 770,019, dated September 13, 1904.

Application filed April 25, 1904. Serial No. 204,666. (No model.)

To all whom it may concern:

Be it known that I, HENRY N. NEIREITER, a citizen of the United States, residing at Decatur, in the county of Adams, in the State of Indiana, have invented certain new and useful Improvements in Tile-Drain Inlets for Surface Water; and I do hereby declare that the following is a full, clear, and exact description of the invention, which will enable others skilled in the art to which it appertains to make and use the same, reference being had to the accompanying drawings, which form part of this specification.

My invention relates to improvements in tile-drain inlets for surface water.

It is well known that the usual means of letting running surface water into tile drains is by a sink-basin built of brick, which is either soon knocked down by stock or soon crumbles under the influence of frost and the elements to which it is exposed and also in times of freshets is soon filled or clogged by driftwood.

The object of my invention is to provide an improved inlet for running surface water for use with ordinary tile drains adapted to let the surface water in freely without danger of interference and derangement thereof by stock or by driftwood and is not affected by the elements.

My invention consists of a sectional and detachable inlet for running surface water, having a closing-cap and provided with a series of lateral perforations adapted to admit the water while excluding driftwood and the like.

The principal feature of my present invention resides in the construction whereby the parts are readily united or detached and at the same time are securely interlocked when in position and are adapted to prevent the entrance of driftwood or interference by stock.

In the accompanying drawings similar reference-numerals indicate like parts throughout the several views, in which—

Figure 1 is a side elevation of my invention in position upon a section of drain-tile broken away in part to show the manner of mounting the same. Fig. 2 is an enlarged detail of the cap broken away in part, showing the means for interlocking the same in position. Fig. 3 is a detail in vertical section, showing a

modified form of the opening in the drainage-tile upon which my invention is arranged.

My invention has one or more, preferably a plurality, of cylindrical parts or sections, 55 the lower one, 1, being adapted to fit snugly a proper boss or flange 4 about an inlet-opening 5 in one of the tiles 3 forming the drain. The lower end of this lowermost section 1 is also preferably provided with the opposite 60 recesses 6 to adapt it to fit down closely upon the body of the tile 3, which may be done when the opening 5 has no flange 4, as when this opening is simply a hole broken in the tile after it has been laid and been long in use. 65

The upper section 2 is mounted upon the section 1 by telescoping their adjacent ends and are rigidly interlocked as follows: On the outer perimeter of the section 1 and near its upper end are arranged a plurality of wedge-like lugs 7, adapted for an interlocked engagement with a corresponding series of recesses 8 upon the inner face of the adjacent end of the telescoping section 2. These sections 1 and 2 are provided with a series of lateral perforations 9 of proper size to freely admit the surface water. 75

The upper section 2 has at or near its upper end a plurality of wedge-shaped lugs similar in form and arrangement to the said lugs 7 80 and has its upper end closed by a cap 11, which has upon the inner face of its flange 12 a plurality of recesses 13, adapted for an interlocking engagement with the said lugs 10, thereby rigidly securing the said cap in position. This 85 cap preferably has its upper surface convex, as shown, and may have a series of suitable perforations therein, if desired, as in case where a considerable quantity of running water is discharged into my improved inlet. 90

In use the upper end of the perforated cylindrical section 2 projects a proper distance above the surface to receive the water without interference with the tillage of the soil about the same. 95

It is obvious that when the sections 1 and 2 are thus interlocked and surmounted by the interlocked cap 11 my improved inlet will be secure against displacement and will prevent all manner of driftwood and rubbish from entering the tile drain with which it is connected. 100

While only one tubular section having a cap

11 may be employed, a plurality of such sections is preferred.

Having thus described my invention and the manner of employing the same, what I desire 5 to secure by Letters Patent is—

1. A tile-drain inlet consisting of a plurality of perforated tubular sections connected with the drain as shown, and united by an interlocking union, and provided upon its outer end 10 with a removable cap secured in position by an interlocking union, all substantially as described.
2. An inlet for tile drains consisting of a

plurality of interlocking perforated sections, united by the union of wedge-shaped lugs and 15 corresponding recesses, and provided with a closing-cap upon its outer end having an interlocked union therewith, as described.

Signed by me at Fort Wayne, Allen county, State of Indiana, this 23d day of April, A. D. 20 1904.

HENRY N. NEIREITER.
